OLIVER MOORE TUCKER AND WILLIAM ALBERT REEVES, OF COLUMBUS, OHIO, ASSIGNEES, BY MESNE ASSIGNMENTS, TO HARTFORD-EMPIRE COMPANY, OF HARTFORD, CONNECTICUT, A CORPORATION OF DELAWARE

TIMING MECHANISM FOR GLASS FEEDERS

Application filed June 30, 1920, Serial No. 392,916. Renewed February 21, 1927.

Our invention relates to timing mechanism for glass feeders and has particular reference to the provision of an automatically operating apparatus which is regulable to take care of practically all conditions which occur or are likely to occur in the feeding of viscous glass. It relates particularly to that type of device wherein the various parts of the glass-feeding device are operable by air under pressure and contemplates the provision of automatic means for regulating the application of such air under pressure to cylinder and piston elements which control and operate the various elements of the feeding device.

The present device is an improvement upon the timing mechanism shown and described in our application filed September 16, 1916, Serial No. 120,429. The cylinders and pistons designed to be actuated under control of the timing mechanism shown herein are the same in principle as the cylinders and pistons which are shown in conjunction with the timing mechanism in the above-mentioned application, although the type of shear-actuating cylinder and piston construction which is shown in an application executed on June 26, 1920, and filed in the Patent Office immediately thereafter is the preferred type of sheer-actuating mechanism that we use in conjunction with the present form of timing mechanism. It will be understood that this timing mechanism may be utilized with various forms of feeding devices, however.

By referring to application Serial No. 120,429 it will be seen that the pistons which actuate the several movable units or elements of our feeder are differential area pistons and that constant air pressure is applied to one area of each piston to maintain the particular element in a given position while air pressure is intermittently applied to a larger area of each piston so as to overcome the constant pressure air and cause the piston to move, these constant and intermittent pressures causing actuation of the different units at proper times. These proper times are determined and controlled by the timer for the reason that the intermittently applied air

passes first through the timing mechanism and is thereby delivered at selected intervals to the various units or elements and more particularly to the larger areas of the piston being actuated.

The present timing mechanism differs from the timing mechanism shown in the case referred to above in that it comprises reciprocable valves as opposed to rotary valves. While the rotary valves shown in this other application were highly satisfactory, they were of such nature that an operator of the machine could by rotating them or any one of them cause them to get out of proper timing relation. In the present timing mechanism with the reciprocable valves, the manual adjustment can only be effected temporarily by an operator because if the operating valves are manually manipulated so as to produce an improper timing, this will automatically be corrected upon the continued operation of the timing mechanism.

A further important advantage of the present timing mechanism is that means are provided for varying the time of starting of the press with relation to the time of drop of the charges. Thus, with some charges, it is desirable to allow the glass to remain in the mold for a longer period of time than it is with others. We have provided a means for regulating the time of trip-off of the press during the continued operation of the machine and without the necessity for stopping any part thereof.

We have also provided a novel form of air lock which operates to positively hold the valves raised after they have once been raised, regardless of whether the machine continues to operate or not, until the continued operation of the machine positively actuates mechanism designed to bring about dropping of the valve.

There are many other features of advantage arising from our novel form of timing mechanism, such as a conserving of the air being utilized and a proper lubrication of the parts of the timing mechanism. These features will appear as this description progresses.

The preferred embodiment of our inven-

Figure 6 is a section taken on line 6—6 of Figure 5.

Figure 7 is a top plan view of the valve base.

Figure 8 is a bottom plan view of the valve block.

Figure 9 is a vertical section taken approximately on line 9—9 of Figs. 7 and 8 and also showing a vertical longitudinal section 25 through the left head and a portion of the timer.

Figure 10 is an enlarged section taken approximately on line 9—9 of Figure 7.

Figure 11 is a section taken on line 11—11 30 of Figure 10.

Figure 12 is a vertical sectional view diagrammatically illustrating one form of glass feeder units comprising a combustion cup and shear structure and also showing cylinder structure for operating the combustion cup.

In the drawings, there is shown a timer box 1 supported upon a suitable standard 2. The timer box has its ends closed by circular 40 heads 3 and 4, while near the center of the timer box there is provided a hollow transverse partition which is normally partially filled with oil for the lubrication of some of the parts contained within the timer box, this 45 chamber being designated 5.

The heads 3 and 4 and the walls of the chamber 5 are fitted with bearings as at 6, within which is journaled a shaft 7 carrying a plurality of cam plates 8. These cam 50 plates 8 are fastened to the shaft 7 by means of set screws 9. The shaft 7 also carries a plurality of cam plates 10 which are loose upon the shaft.

The shaft 7 likewise carries a single cam plate 11 fastened thereto with set screws 9, this cam plate 11 being shown (Figure 2) near the right-hand end of the shaft 7. The shaft 7 is driven from a source of power by any suitable gearing and is shown as being 60 driven from a variable speed motor 12, through a shaft 13, worm and worm wheel, respectively designated 14 and 15, the worm wheel being mounted upon shaft 7.

The cam plates 8 and 10 are in pairs and 65 carry gears 16 upon their opposing faces.

These gears 16 are in mesh with pinions 17. Each pinion 17 is mounted upon a depending pin 18 carried by a block 19. This block 19 is fitted upon the shaft 7 and this shaft 7 turns therein.

The ends of the pins 18 extend into the ends of a yoke member 20 so that the pinions upon the two adjacent pairs of cam plates 8 and 10 may be adjusted in unison.

The adjustment of this yoke member 20 to regulate the position of the pinions and the consequent relation of the cam plates is rendered possible by the provision on the yoke of two depending spaced lugs 21 which are drilled transversely for the reception of a swivel pin 22. This swivel pin 22 is likewise drilled transversely and is threaded for the reception of a hand-operated screw such as is shown at 23 in Figure 4. The pin 22 is so fitted that it will turn freely in the lug 21 and the threaded rod is shouldered as at 24 in Figure 4. Beyond this shoulder, this screw rod is reduced as at 25 and passes through a transverse hole such as 26 in the pin 27 (Figure 4). The handle for manipulating the screw rod for these particular pairs of cam plates desirably take the form of a hand wheel 28 rigidly secured to the screw rod and separated from the flattened surface of such a pin as 27 by means of spring washers such as shown at 29 in Figure 4. This construction permits of a ready regulation of the position of the yoke 20 so as to alter the position of the pinions and to consequently alter the relation of the rigid and loose cam plates with relation to each other. Thus by turning the hand wheel 28, the yoke 20 and consequently the pins 18 will be given a concentric motion around the shaft 7. Furthermore, the swiveled pin 27 permits free movement of the yoke member.

The cam plates are of circular form and are provided at determined intervals around their edges with apertures 8^a (see Figures 9 and 11) for the reception of pins 30 threaded for the reception of nuts 31 and provided with shoulders 32 so that the plates will be clamped between the nuts 31 and the shoulders 32 and these pins will rotatably support cam rollers 33. The actual number of apertures 8^a provided in these cam plates to permit of adjustment of the rollers as desired have not been shown because a different number of holes may be provided for different plates. However, a sufficient number of holes or apertures are provided to permit of any necessary adjustment and these holes are so located that the edges of the rollers will project beyond the periphery of the plate to operate with the stems of poppet valves which are thus actuated to control the main differential area valves that in turn control the application of intermittent air to the cylinders which govern the movable units of the feeding device.

The differential area valves and their cooperative mechanism which operate the cylinders that move the flaming cup of our feeder horizontally and vertically are practically identical, one valve structure being used for controlling the intermittent introduction of air under pressure to the horizontal cylinder and another being used for controlling the intermittent introduction of air under pressure to the vertical cylinder. The valves which operate the horizontal and vertical cylinders are respectively mounted in casings 34 and 35. The casing 34 and the mechanism enclosed thereby is shown best in Figures 9, 10 and 11. This is the structure which controls the introduction of air under pressure to the horizontal cylinder and, inasmuch as this structure is substantially the same as the structure which controls the introduction 20 of air to the vertical cylinder, it will only be necessary to describe the structure shown in Figures 9, 10 and 11 with the understanding that the description will likewise apply to the structure contained within the casing 35. An understanding of this structure will be facilitated by the showing of the valve base, in Figure 7, and by the bottom plan view of the valve block in Figure 8.

Referring to Figure 12, a spout forming a part of a glass feeder is designated 90 and is provided with a bushing and an aperture as is conventionally shown at 91 and 92. In this figure a combustion cup 93 is shown positioned below the bushing 91 and is so mounted as to be oscillated back and forth from a position below the bushing and also to be reciprocated at any time during such oscillation. The combustion cup is given vertical movement by the vertical piston and cylinder construction 94, and is given horizontal or oscillation movement by the horizontal piston and cylinder construction 95. In the form of cylinder shown in Figure 12 it will be noted that the pistons are differential area pistons. Constant pressure air is designed to be supplied to one area of the piston in the vertical cylinder 94 and intermittent air under pressure is introduced to the other area of the piston by means of the fluid operated valve structure mounted in the casing 35. The piston in the horizontal cylinder 95 is similar in construction to the piston in cylinder 94 and the valve in the casing 34 controls the introduction of air under pressure to this horizontal cylinder. It will be understood that any suitable shear structure such as 96 may be positioned beneath the feeder orifice and may be operated by horizontal cylinder and piston structure similar to the structure shown in the cylinders 94 and 95. It will also be understood that air may be automatically introduced under pressure to this shear cylinder in the same manner as introduced into the combustion cup cylinder.

ders and that the proper time for the introduction of such air may be determined and controlled by the timer.

The casing 34 is constructed to contain a differential area piston 36 which is provided with two conical valves 37 and 38 and which carries a piston head construction 39 upon its base. The valve 37 is designed to cooperate with a valve seat 40 and the valve 38 is designed to cooperate with a valve seat 41. In between these valve seats 40 and 41 there is provided a passage 42 which is connected at its upper end to a pipe 43 that leads to the horizontal cylinder and particularly to the space in front of the larger area of the piston contained in such cylinder.

Below the valve seat 41 there is provided a passageway 44 that communicates with exhaust ducts 45. The exhaust ports 45 lead directly into the timer box and the exhaust air which they deliver into such timer box is sufficiently laden with oil to effectively lubricate the gears, rollers and pins of the timing mechanism. Oil becomes mixed with this exhaust air preferably by interposing a lubricating device (not shown) in the constant air line (not shown) which connects with the constant air inlet pipe 52. Obviously, with this construction, the intermittent air admitted to the operating cylinders and exhausted therefrom through pipe 43, will carry such oil in suspension.

Supplemental to this differential area valve piston we have provided poppet valves 46 and 47. These poppet valves are pressed downwardly against their seats by coil springs 48 and 49 bearing in sockets provided therefor. These poppet valves are also provided with depending stems 50 and 51 which extend downwardly through the top of the timer box and into juxtaposition to the cam plates 8 and 10 which are rotating in opposite directions. The lower ends of these stems 50 and 51 are so located that they will be elevated by the rollers 33 carried upon the cam plates 8 and 10.

Leading into the upper end of the casing 34 is a constant pressure air pipe 52 which delivers air under pressure to a chamber 53 above the valve seat 40 and the valve 37. This chamber 53 is provided with a bypass 54 leading downwardly to the poppet valve 47.

In operation of this structure, the rotation of the plate 10 brings its roller into contact with the stem 51 of the poppet valve and this raises the poppet valve and permits a free passage of the air from pipe 52 and chamber 53 through bypass 54 past poppet valve 47 and through duct 55 into the space beneath the piston 39 of the differential area piston. Until the raising of this poppet valve, the differential area piston has been held down by the constant pressure air acting upon the upper end of the valve 37 in the chamber 53. However, the admission of air to the space 56

below the differential area valve serves to immediately overcome the pressure in the chamber 53 due to the fact that the area to which the air is applied upon the piston 39 is greater than the area of the upper side of the valve 37. The result is that the piston 39 immediately moves upwardly and unseats the valve 37 at the same time seating the valve 38. Then the air under pressure from chamber 53 passes by the valve 37, into the passage 42 and thence by way of the pipe 43 to the large area of the piston in the horizontal cylinder. In the continued operation of the timer, the roller 33 on cam plate 8 comes into contact with the stem 50 of poppet valve 46 and raises this poppet valve from its seat. Immediately, the air within the chamber 56 is exhausted by way of passages 57 and 58, passing by the poppet valve and into the timer box. When this occurs, the differential area valve immediately drops due to the pressure in chamber 53, seating valve 37 and unseating valve 38. The result is that the pipe 43 and the passage 42 are connected to the passage 44 and to the exhaust ports 45 so that the air in front of the larger area of the piston in the horizontal cylinder is forced backward through pipe 43, passage 42 past valve 38 into passage 44 and through exhaust port 45 into the timer box.

An additional feature of this differential area valve consists in the provision of means for maintaining the valve raised by what we have termed an air lock. It takes the form of a port 59 and a passage 60 which leads from the passage 42 through the wall of the valve and into the space of chamber 56. The result is that when the valve is raised and air is permitted to pass from the chamber 53 into the passage 42 and thence to the pipe 43 a portion of this air enters the port 59 and passes through the passage 60 into the space of chamber 56. The air thus passing into the chamber 56 is sufficient to compensate for all leakage and to maintain sufficient pressure beneath the differential area valve to lock it in raised position. However, the port 59 is of a lesser diameter than the passage 57 so that when the poppet valve 46 is raised, the air will exhaust with sufficient rapidity, in spite of the air being delivered to chamber 56 by the passage 60, so that the differential area valve will drop without delay.

At the extreme right-hand end of the shaft 7 there is provided a cam plate and associated mechanism which has the combined function of controlling the operation of the cylinder and piston which operate the shears and of controlling the operation of the trip-off cylinder which is common to most forming machines. The cam plate has been designated 11 and carries rollers 61 and 62 which are mounted thereon in the same manner as are the rollers 33 on the cam plates 8 and 10. 11
10 Also, holes are provided around the cam plate

adjacent to its edge so that these rollers may be adjusted as desired. This structure is shown best in Figures 4, 5 and 6. The knife-operating cylinder and the mechanism associated therewith is of such a nature that a complete reciprocation of the knife-operating piston follows each introduction of intermittent air to the knife-operating cylinder for the reason that the knives are normally held open by constant pressure air, are closed when an impulse of air from the timer is admitted to the control valve which trips the control valve and it in turn admits the intermittent air to the greater area of the piston, and are then again opened as soon as the cutting action is completed by the automatic action of the structure of the shear-actuating mechanism as described in the above-identified application. This means that, as far as the intermittent operation of the shears is concerned, the timer is only required to deliver intermittent impulses of air under pressure to the control valve.

The cam roller 61 brings about the introduction of these intermittent impulses of air under pressure by contact with and raising of the stem 63 of the poppet valve 64, which poppet valve is normally held in position against its seat by coil spring 65. When this poppet valve 64 is lifted by contact of the cam roller 61 with the stem 63, air under pressure is admitted from the constant supply pipe 66 through the stop cock 67 which has been previously turned to permit of the passage of this air, past the valve seat and through the passage 68 into the pipe 69 which is shown in Figure 4 and which leads to the control valve of the shear. When this occurs, the knives or shears move into cutting relation and then automatically reverse.

The mechanism for controlling the tripping off or initiation of movement of the forming machine is operated by the cam roller 62 on the cam plate 11. This cam roller is designed to contact with and force downwardly the stem 70 of a poppet valve 71 which is normally held against its seat by means of a coil spring 72. When this poppet valve is forced downwardly by contact of the cam roller 62 with the stem 70 the constant pressure air from the pipe 66 passes through the passage in the stop cock 73, through the flexible hose 74, through the elbow 75, through the passage 76 past the poppet valve and then through the passage 77 and flexible hose 78 to a cylinder 71^a and piston 71^b construction which is common to present day forming machines and which trips off such forming machine after each charge is dropped into a mold. The form of tripping-off mechanism may be varied, but in the form shown in Figure 3, the piston 71^b may be of differential area construction and having fluid pressure constantly applied to its smaller surface and intermittently applied

to its larger face. When the valve 71 is opened, fluid pressure is admitted through pipe 78 to the large face of the differential piston 71^b, moving the piston 71^b and its stem 71^c outwardly. As the stem 71^c moves outwardly it may actuate, trip, or render effective any suitable mechanism such as electrical apparatus, levers, gears, clutch mechanism, a valve or valves et cetera, for unlocking or starting the shaping machine in motion, all of which, obviously, depends upon the construction of the particular shaping machine employed, as is well recognized by those skilled in the art. The reverse movement of the piston 71^b may be effected by the provision of a bleed port 71^d in the cylinder head 71^c, which permits the fluid on large face of the piston 71^b to exhaust upon the closing of valve 71. It is to be understood that the bleed port 71^d is not of such size as to interfere with the movement of the piston 71^b when pressure is admitted to its large face. Upon the exhaust of fluid from the large face of the piston, the constant pressure acting on its smaller face will move it to the original position (as shown) ready for the next operation in the succeeding cycle.

The poppet valve 71 and the passages 76 and 77 are mounted and provided in an element which is swung from the bearing 6 and which comprises two sections 79 and 80 (see Figures 5 and 6). This element is angular in section as shown in Figure 5 and immediately adjacent to the poppet valve is provided with a bifurcate portion 81 carrying a swivel pin 82 which is apertured as at 83 and which has this aperture 83 threaded for the reception of the screw rod 23 that has been already described. Rotation of this screw rod will serve to swing the depending element 79 and its portion 80 about the bearing 6. This will result in changing the position of the poppet valve and its stem 70 so that it will be actuated either sooner or later, depending upon the direction in which the screw rod is turned. Thus, by turning the handle 84 of this screw rod, the time of actuation of the poppet valve and consequently the time of tripping off of the forming machine may be adjusted and this adjustment may be effected while the glass feeder and the timing mechanism is in operation.

It will be noted that the member 79 is held firmly against the plate 4 by means of a screw pin 85 extending through a slot 86 in the plate 4 and cooperating with a leaf spring 87 that is placed between the head of the pin 85 and the element 4. This structure is such as to permit of the requisite movement of the member 79 about the bearing 6 for all necessary purposes of adjustment and it also serves to maintain this member 79 properly spaced from the cam plate 11 as at 88.

It will be understood that in the description of this invention the term "forming ma-

chine" has been used for the purpose of facilitating description. It is intended to include presses, press and blow machines, bottle machines, and, in fact, practically any type of machine capable of receiving a charge from a feeding device and forming this charge either wholly or in part.

The stop cocks 67 and 73 are provided so that either the shears or the press or forming machine may be cut out of operation independently. However, it will be understood that in the practical operation of our device it is not feasible to stop the operation of the shears without first stopping the operation of our flaming cup.

Having thus described our invention, what we claim is:

1. In glass feeding apparatus, a differential area valve, a chamber for maintaining constant fluid pressure in contact with the smaller area of said valve, a chamber for the intermittent reception of fluid to effect the intermittent application of such fluid under pressure to the larger area of said valve to move the same, and a port which, upon said movement of said valve conducts fluid continuously to the chamber which effects the intermittent application of fluid to the larger area of said valve whereby the said valve is maintained in the position to which it has been moved, and means for releasing the fluid from the said last-mentioned chamber to permit return of the valve to normal position.

2. Timing mechanism for glass feeding apparatus comprising a fluid distributing valve mechanism, a differential valve for controlling the introduction and exhaust of fluid to the driving units of the glass feeding apparatus, and a pair of cam plates operating together to actuate said fluid distributing valve mechanism, the said cams being adjustable with relation to each other to vary the time of introduction and exhaust of fluid with relation to each other.

3. Timing mechanism for glass feeding apparatus comprising means for intermittently supplying fluid pressure to the trip-off cylinder of a forming machine, said means embodying a poppet valve and a cam plate, and means for adjusting the position of the poppet valve so as to vary the instant when it is operated by the cam plate.

4. Timing mechanism for glass feeding apparatus comprising means for intermittently supplying fluid pressure to the shear structure of the feeding apparatus and to the trip-off means of a forming machine, said means embodying poppet valves and a cam plate, and means for adjusting the position of the trip-off poppet valve relative to said cam plate.

5. Timing mechanism for glass feeding apparatus comprising means for intermittently supplying fluid pressure to the shear structure of the feeding apparatus and to the trip-

off cylinder of a forming machine, said means embodying poppet valves, a cam plate and cam rollers thereon, said rollers being relatively adjustable of each other, and means for adjusting the position of the trip-off valve independently of said rollers.

6. In combination with glass machinery having a plurality of movable units with operating mechanism therefor, a source of fluid pressure, intermediate fluid actuated valves for automatically regulating the application of fluid to the operating mechanism of said units, and a series of cams for controlling the application of fluid to said valves whereby the application of fluid to said operating mechanism is regulated.

7. In combination with glass machinery having a plurality of movable units with operating mechanism therefor, a source of fluid pressure, intermediate fluid actuated valves for automatically regulating the application of fluid to the operating mechanism of said units, and a series of cams for controlling the application of fluid to said valves whereby the application of fluid to said operating mechanism is automatically controlled.

8. In glass feeding apparatus, a differential area valve, a poppet valve to admit fluid under pressure beneath said differential area valve, a second poppet valve to exhaust fluid under pressure from beneath said differential area valve, and means for operating said second poppet valve at adjustable intervals.

35 9. In a timer mechanism for glass working machinery, valves controlling the operation of said machinery, a revolving member adapted to actuate said valves, and means for shifting one of said valves in an arc concentric with the axis of rotation of the revolving member, whereby the relative time of actuation of said valves may be varied.

10. In a timer mechanism for glass working machinery, a valve controlling the operation of an operating unit of such machinery, a revolving member adapted to actuate said valve, means for supporting the rotary member and the valve, and means for shifting the valve in an arc concentric with the axis of rotation of the revolving member whereby the time of actuation of said valve may be varied.

11. In a timer mechanism for glass working machinery, valves controlling the operation of such machinery, a revolving member adapted to actuate said valves, means for supporting the rotary member and the valves, and means, including an arcuate slot in said supporting means and clamping means associated therewith, for shifting one of said valves in an arc concentric with the axis of rotation of the revolving member and for aligning the contact portion of said valve with the actuating portion of the revolving member, whereby the relative time of actua-

tion of the controlling valves may be varied.

12. In a timing device for the control of glass working machinery provided with fluid pressure operating means, a rotary element, a support therefor, a controlling valve mounted upon said support and adapted to be moved in an arc concentric with the axis of rotation of the rotary element, an arcuate slot in said support, a clamping member associated with said valve and co-operating with the slot for determining the position of said valve, whereby said valve may be moved in the path of the rotary element to vary the time of actuation of said valve.

13. In a timing device for the control of glass working machinery provided with fluid pressure operating means, a rotary element, a support therefor, a controlling valve adapted to be actuated by said rotary element and provided with flexible air connections to a source of fluid pressure supply and to an operating unit of the machinery, and means, including an arcuate slot in said support and a clamping means associated with the controlling valve and co-operating with said slot, for moving said valve concentrically with the axis of rotation of the rotary member and in the path thereof, whereby the time of actuation of said valve may be varied.

14. In a timer for controlling the movements of the operating units of a fluid pressure operated glass working machinery, a rotary actuating element, a support therefor, valves adapted to be actuated by said rotary element, so mounted on said support as to permit changes in their relative angular positions about the axis of rotation of the rotary element, flexible air connection to one of said valves and means for moving one of said valves relative to another, whereby the relative time of actuation of said valves may be varied.

15. In a timing device, the combination of a rotary shaft having contact members mounted thereon, a support for control elements provided with a bearing hub for the shaft, an operative control element rigidly mounted on the support and in the path of movement of one contact member, another operative control element movably mounted on the bearing hub, and means for adjusting the movable control element concentrically with the axis of the shaft and in the path of movement of the other contact element to change the relative time of operation of the control elements.

16. In a rotary timing device for pneumatically operated mechanism, valves for controlling the admission of fluid pressure to the mechanisms, a rotary actuator member for periodically actuating the valves, a stationary support for one of the valves, a bearing on the stationary support for the rotary member, a movable support for another of said valves, said movable support being

5 mounted concentric with the axis of the rotary member, means for clamping the movable support to the stationary support, and means for shifting the movable support to change the time of actuation of the valve carried thereby.

10 17. In combination with pneumatically operated glassworking machinery having a plurality of glassworking units, a source of fluid pressure supply, a stationary valve for controlling the admission of fluid pressure to one unit, a movable valve for controlling the admission of fluid pressure to another unit, flexible conduits for distributing fluid pressure to the glass making unit through said valve, a rotatable member carrying separate contact elements each adapted to periodically actuate one of the valves, a bearing for supporting said movable valve and said rotary member, means for swinging the movable valve in an arc concentric with the axis of the rotatable member to change its time of operation and means for yieldably clamping the support in the path of one of the rotatable 25 contact elements.

15 18. In a timing device for glassworking machinery, the combination of valves for transmitting fluid pressure to separate glassworking units, a rotatable member having contact members mounted thereon, said contact members being arranged to revolve in different planes and each adapted to periodically actuate a valve, means for shifting one of the valves in an arc concentric to the axis 30 of rotation of the rotatable member and in the path of movement of its contact member, whereby the relative time between the actuation of the valves may be varied.

20 19. In combination with pneumatically operated glassworking machinery having a plurality of units, a source of fluid pressure supply, valves for controlling the admission of fluid pressure to the glassworking units, a valve actuator associated with each valve, a rotary member having contact elements for periodically engaging the valve actuators, means for changing the time of operation of one of the valves, by moving said valve along the path of its contact element.

25 20. In combination with pneumatically operated glassworking machinery having a plurality of units, a source of fluid pressure, valves for controlling the admission of fluid pressure to each of the glassworking units; a valve actuator associated with each valve, a rotary member having contact elements for periodically engaging the valve actuators, one of said valve units being mounted concentrically of the axis of said rotary member, means for shifting the last named valve circumferentially of the rotary member to change the period of actuation of the valve, and a flexible air connection between the movable valve and the source of fluid pressure.

30 21. In a timing device for glassworking

machinery, the combination of valves for transmitting fluid pressure to separate glassworking units, a rotatable member having contact members mounted thereon and arranged to revolve in different planes and each adapted to periodically actuate a valve, means for shifting one of the valves in an arc concentric to the axis of rotation of the rotatable member and in the path of movement of its contact member while the member is rotating, whereby the relative time of the actuation of the valves may be varied during the operation of the glass working machinery.

35 22. Timing mechanism for glass feeding apparatus comprising means for intermittently supplying fluid pressure to the trip-off cylinder of a forming machine, said means embodying a valve and a rotary member, and means for adjusting the position of the valve so as to vary the instant when it is operated by the said member.

40 23. Timing mechanism for glassworking apparatus, comprising means for intermittently supplying fluid pressure to a plurality of operating units thereof, said means including a rotary member and valve structure having a common axis, and means for varying the angular position on said axis of said valve structure.

45 24. Timing mechanism for glass feeding apparatus comprising means for intermittently supplying fluid pressure to the shear structure of the feeding apparatus and to the trip-off means of a forming machine, said means embodying valves and a rotary actuator, and means for varying the position of the valve supplying pressure to the trip-off means.

50 25. Timing mechanism for glassworking apparatus comprising means for intermittently supplying fluid pressure to the shear structure of the feeding apparatus and to the trip-off cylinder of a forming machine, said means comprising controlling valves, a rotary cam plate and cam rollers thereon, said rollers being adjustable on the cam plate relative to each other and means for adjusting the position on its cam path of the valve supplying the trip-off cylinder, whereby the relative time of actuation of the valves may be varied independently of the adjustment of the cam rollers.

55 26. The combination with a timing device provided with a pair of moving contact members, means for adjusting the relation between said contact members, a fixed control element, a movable support and another control element mounted thereon, each of said control elements being actuated by one of said contacts, whereby by shifting said support the relative timing of the two control elements may be adjusted.

60 27. The combination of a timing device provided with a pair of moving contact mem-

bers, a fixed control element, a movable support, a control element mounted on said support, each of said control elements being in the path of one of said contact members, and means for shifting said support to change the position of its control element on the path of its contact member, whereby the timing of said control elements may be adjusted while the timing device is in operation.

28. The combination with a timing device provided with moving contact members, a fixed support adjacent to the timing device, an operative-control element mounted on said fixed support and in the path of one of said contact members to be periodically actuated thereby, a second support movably mounted adjacent to said timing device, and a second control element mounted on said second support and in the path of another of said contact members to be periodically actuated thereby, whereby by shifting said second support the time relation between said elements may be adjusted.

29. The combination with a timing device provided with moving contact members, a fixed support adjacent to the timing device, an operative-control element mounted on said fixed support and in the path of one of said contact members to be periodically actuated thereby, a second support adjacent to said timing device, a second operative-control element mounted on said second support and in the path of another of said contact members to be periodically actuated thereby, and means for shifting said second support relative to the timing device whereby the relative timing of said elements may be adjusted while the timing device is in operation.

30. The combination with a timing device provided with moving contact members, means for adjusting the relative movements of said contact members, a fixed support adjacent to said timing device, an operative-control element mounted on said fixed support and in the path of one of said contact members to be periodically actuated thereby, a movable support adjacent to said timing device, and a second operative-control element mounted on said movable support and in the path of another of said contact members to be periodically actuated thereby, whereby the relative timing of said elements may be adjusted.

31. The combination with a timing device provided with moving contact members, means for adjusting the relative movements of said contact members, a fixed support adjacent to said timing device, an operative-control element mounted on said fixed support and in the path of one of said contact members to be periodically actuated thereby, a second support adjacent to said timing device, a second operative-control element mounted on said second support and in the path of another of said contact members to be periodically actuated thereby.

be periodically actuated thereby, and means for shifting said second support relative to the timing device whereby the relative timing of said elements may be adjusted while the timing device is in operation.

32. In a rotary timing device, the combination of revolving contact members, an operative-control element mounted in the path of one of said contact members, a second operative-control element mounted in the path of another of said contact members, and means for shifting one of said elements in an arc concentric with the path of its associated contact member whereby the relative timing of the members may be adjusted.

33. In a rotary timing device, the combination of revolving contact members, a fixed support mounted adjacent to the device, an operative-control element mounted on said support and in the path of one of said contact members to be periodically actuated thereby, a second support adjacent to said device and movable in an arc concentric with the axis of the timing device, and a second operative-control element mounted on said second support in the path of another of the contact members to be periodically actuated thereby, whereby the relative timing of said elements may be adjusted.

34. In a rotary timing device, the combination of revolving contact members, a fixed support adjacent to the timing device, an operative-control element mounted on said support and in the path of one of the contact members to be periodically actuated thereby, a second support adjacent to the timing device, a second operative-control element mounted on said second support and in the path of another contact member to be periodically actuated thereby, and means for shifting said second support in an arc concentric with the axis of the timing device whereby the relative timing of said elements may be adjusted.

35. In a rotary timing device, the combination of contact members revolving in unison about a common axis, means for adjusting said contact members about said axis, an operative-control element fixedly mounted in the path of one of said contact members to be periodically actuated thereby, and a second operative-control element mounted in the path of another contact member and movable in an arc concentric with the path of its associated contact member whereby the relative timing of said elements may be adjusted.

36. In a rotary timing device, the combination of contact members revolving in unison about a common axis, means for individually adjusting said contact members about an axis, an operative-control element fixedly mounted in the path of one of said contact members to be periodically actuated

thereby, a second operative-control element mounted in the path of another of said contact members to be periodically actuated thereby, and means for shifting said second element in an arc concentric with the axis of the timing device whereby the relative timing of the elements may be adjusted.

37. A timing mechanism for controlling the operation of pneumatically operated glass feeding apparatus, comprising a fluid pressure operated control valve for controlling the introduction and exhaust of fluid pressure to and from the feeder, means associated with the valve for regulating the application of fluid pressure to said valve so as to produce a desired periodic operation thereof, and a rotatable member for controlling the operation of the regulating means and adapted automatically to restore the periodicity of the control valve should such periodicity be temporarily disturbed by a manual actuation of said regulating means.

38. A timing mechanism for controlling the operation of pneumatically operated glass feeding apparatus, comprising a fluid pressure operated valve, auxiliary valves associated with the control valve for regulating the application of fluid pressure to said valve so as to produce a desired periodic operation thereof, and a rotatable member for controlling the relative times of the movements of the auxiliary valves so that manual operation of any of said auxiliary valves will only temporarily disturb the periodicity of the control valve.

39. A timing mechanism for controlling the operation of pneumatically operated glass feeding apparatus, comprising a fluid pressure operated control valve, auxiliary valves associated with the control valve for regulating the application of fluid pressure to said valve so as to produce a desired periodic operation thereof, and a series of cams for controlling the relative times of the movements of the auxiliary valves so that manual operation of any of said auxiliary valves will only temporarily disturb the periodicity of the control valve.

In testimony whereof we hereby affix our
50 signatures.

OLIVER M. TUCKER.
